UNITED STATES PATENT OFFICE.

GEORGE M. LIGHT, OF POMEROY, WASHINGTON.

LAND-SCRAPER.

SPECIFICATION forming part of Letters Patent No. 633,860, dated September 26, 1899.

Application filed June 2, 1899. Serial No. 719,117. (No model.)

To all whom it may concern:

Be it known that I, GEORGE M. LIGHT, a citizen of the United States, residing at Pomeroy, in the county of Garfield and State of Washington, have invented a new and useful Land-Scraper, of which the following is a specification.

The invention relates to improvements in land-scrappers.

10 The object of the present invention is to improve the construction of land-scrappers and to provide a simple and comparatively inexpensive one adapted for general leveling purposes and designed especially for leveling fields after the same have been plowed and capable of breaking the lumps and of packing the earth sufficiently to obviate the necessity of using a land-roller.

20 A further object of the invention is to provide a scraper of this character which will possess great strength and durability and which may have its blades readily adjusted and arranged at different inclinations to effect the proper operation or action on the 25 soil.

The invention consists in the construction and novel combination and arrangement of parts hereinafter fully described, illustrated in the accompanying drawings, and pointed 30 out in the claims hereto appended.

In the drawings, Figure 1 is a perspective view of a land-scraper constructed in accordance with this invention. Fig. 2 is a plan view. Fig. 3 is a detail view illustrating the 35 manner of hinging the scraper-blades to the connecting-bars.

Like numerals of reference designate corresponding parts in all the figures of the drawings.

40 1 designates a transverse bar located at the front of the scraper and having the sections 2 thereof connected with it and forming a main whiffletree, to which the draft is applied, and the said sections 2, which may be 45 of any desired number, consist of front and rear scraper-blades 3 and 4, connected by the means hereinafter described and designed to be arranged at an inclination, as clearly illustrated in Fig. 1 of the accompanying drawings.

50 In the accompanying drawings a scraper consisting of three sections is illustrated, and the clevis or draft attachment is arranged cen-

trally of the main whiffletree-bar 1, a three-horse evener being designed to be provided for equalizing the draft of three horses. One 55 horse is to be provided for each of the sections of the scraper, and when four sections are used a pair of doubletrees may be coupled to the main whiffletree-bar at points equidistant of the euds thereof instead of providing 60 a central clevis or draft attachment which may be of any desired construction.

The front and rear scraper-blades 3 and 4 are connected by central and side longitudinal bars 6 and 7, provided at their ends with 65 eyes 8 and secured to the inner faces of the scraper-blades, near the upper edges thereof, by pintles 9, passing through the eyes and having their ends enlarged and secured to the rear faces of the front scraper-blades and to 70 the front faces of the rear scraper-blades. The longitudinal bars are supported by forwardly-converging braces 10, secured at their rear ends to the side connecting-bars, near the rear terminals thereof, and connected at their 75 front ends to the central bar 6, near the front end thereof.

The front and rear blades 3 and 4 are provided near their centers with upwardly-extending bifurcated arms 11 and 12, which are 80 connected with an operating or shifting lever 13 by a bar 14, provided between its ends with a curved ratchet 15, located above the fulcrum-point 16 of the operating or shifting lever. The operating or shifting lever, which 85 is fulcrumed on a suitable bolt or pivot 16, has its lower end arranged within a keeper or bracket 17, and it is pivoted at 18 to the connecting-bar 14. The curved ratchet, which is provided at its upper edge with suitable 90 teeth or notches, is engaged by a spring-actuated dog or detent carried by the operating lever and connected with a suitable latch-lever 19, located adjacent to the handle or grip of the operating lever and adapted to be 95 grasped simultaneously with the same. By shifting the lever forward and rearward the inclination of the scraper-blades may be changed, as will be readily apparent.

The connecting-rods 14 are provided at their 100 front ends with series of perforations 20, adapted to receive the pivots 21, which connect the bars 14 with the arms 11, and by adjusting the pivots 21 in the different perforations

of the bars 14 the front scraper-blade 3 may be set at a different angle or inclination from the rear scraper-blade. This permits the front scraper-blades to be arranged at a slight 5 inclination and to be set nearly vertical to adapt them for leveling the land and for breaking the lumps, and by arranging the rear scraper-blades at a greater inclination they will operate to pack the soil after the same 10 has been leveled by the front scraper-blades.

The front and rear scraper-blades of each section are designed to be of different lengths, as clearly illustrated in Fig. 2 of the accompanying drawings, in order to break the joints 15 and arrange the spaces or openings between the adjacent ends of the front scraper-blades out of alinement with those of the rear scraper-blades, so that any ridge left by the front blades will be leveled by the rear ones. By 20 this arrangement the scraper is enabled to leave the surface of the land operated on perfectly smooth and free from ridges.

The front scraper-blades are provided at their upper edges with clevises 22, which engage rings 23 of short chains 24, extending from the upper edges of the front scraper-blades to the transverse bar 1 and secured to the latter by any suitable fastening devices, such as staples, clips, or the like.

30 It will be seen that the land-scraper, which is simple, inexpensive, strong, and durable, while being designed for general leveling purposes is especially adapted for operating on fields during the process of cultivation and 35 that it is capable of leveling the soil, breaking the lumps, and packing the earth. The scraper-blades may be readily shifted and arranged at the desired inclination, and the angle or inclination of the front scraper-blades 40 may be different from the rear scraper-blades, whereby the front ones will level the soil and break the lumps and the rear ones will be caused to pack the earth. The number of sections may be varied, and by employing 45 blades of different lengths for each section the spaces or intervals between the blades will be out of alinement, and any ridges left by the front scraper-blades will be leveled by the rear ones.

50 Changes in the form, proportion, size, and the minor details of construction within the scope of the appended claims may be resorted to without departing from the spirit or sacrificing any of the advantages of this invention.

55 What is claimed is—

1. A scraper provided with front and rear blades and having means whereby the blades may be set at different inclinations to cause 60 the front blade to level the soil and break the lumps, and the rear blade to pack the earth, substantially as described.

2. A scraper comprising front and rear blades, connections between the blades having the latter hinged to them, and operating 65 mechanism mounted on the said connections and adapted to adjust the blades and hold the same at the desired inclination, substantially as described.

3. A scraper composed of sections having 70 front and rear blades of different lengths, whereby the spaces or intervals between the adjacent ends of the front blades will be out of alinement with those of the rear blades, substantially as described.

4. A scraper comprising a series of sections having front and rear blades hingedly mounted and adapted to be arranged at an inclination, operating mechanism mounted on the sections and connected with the front and 80 rear blades, a transverse bar arranged at the front of the scraper and forming a main whiffletree, and connections between the upper portions of the front blades, and the transverse bar, substantially as described.

5. A scraper comprising the front and rear blades hingedly mounted, a longitudinal bar adjustably connecting the blades and adapted to set the same at different inclinations, and operating mechanism connected with the longitudinal bar and adapted to shift the blades simultaneously, substantially as described.

6. A scraper comprising front and rear blades hingedly mounted and provided with upwardly-extending arms, connections between the blades, a longitudinal bar pivoted to the arm of the rear blade and adjustably connected to the arm of the front blade, an operating-lever fulcrumed on the said connections and connected with the longitudinal bar, and means for locking the operating-lever, substantially as described.

7. A scraper comprising front and rear blades, the central and side connecting-bars hinged to the blades, braces connecting the 105 said bars, and operating mechanism mounted on the central bar and connected with the blades, substantially as described.

8. A scraper comprising a series of sections composed of front and rear blades and connecting-bars having the blades hinged to them, operating-levers fulcrumed on the connecting-bars, longitudinal bars connecting the levers with the blades and a transverse bar arranged at the front of the scraper and connected with the front blades, substantially as 110 described.

In testimony that I claim the foregoing as my own I have hereto affixed my signature in the presence of two witnesses.

GEORGE M. LIGHT.
